FOLDING TABLE

William A. Snyder, Los Angeles, Calif.

Application December 18, 1933, Serial No. 702,930

8 Claims. (Cl. 311—96)

My invention relates to a folding table and has for its principal objects, to generally improve upon and simplify the construction of the existing forms of folding tables, to provide a table having a folding top that may be manipulated so as to materially increase or decrease its size and further, to provide a table of the character referred to that may be conveniently folded into compact form so as to occupy comparatively little space 10 when closed and packed for storage or transportation.

Further objects of my invention are, to provide a folding table that is especially designed for use as a camp table or as a card or tea table, further, to provide a folding table having an auxiliary frame that is removably positioned on the table top and utilized for the support of various articles that are generally used in the service of meals and further, to provide a folding table with 20 folding braces between the legs and between the table top and legs so as to provide a strong and substantial structure when the table is open for use.

With the foregoing and other objects in view 25 my invention consists in certain novel features of construction and arrangements of parts that will be hereinafter more fully described and claimed and illustrated in the accompanying drawings in which:

30 Fig. 1 is a side elevational view of the table open for use.

Fig. 2 is a plan view of the table top as the same appears when folded into its smallest compass.

35 Fig. 3 is a plan view of the table top as the same appears when fully open.

Fig. 4 is an enlarged cross section taken on the line 4—4 of Fig. 1 and showing the auxiliary supporting frame that is removably mounted on the central portion of the table top.

40 Fig. 5 is an enlarged cross section taken on the line 5—5 of Fig. 4.

Fig. 6 is an enlarged cross section taken on the line 6—6 of Fig. 1 and showing the hinged table top sections folded into position on top of the sliding table top sections.

45 Fig. 7 is a cross section taken on the line 7—7 of Fig. 6.

Fig. 8 is a cross section taken on the line 8—8 of Fig. 6.

50 Fig. 9 is an enlarged detail elevational view showing the connections between the two frames of the table, also the connections between the table legs and said frames.

55 Fig. 10 is an enlarged elevational view of the table.

Referring by numerals to the accompanying drawings which illustrate a preferred embodiment of my invention, 10, 10 designate identical rectangular frames preferably formed of wood and the inner end rails 11 of these frames are connected by a hinge or hinges 12 arranged so as to permit the frames 10 to swing downwardly into position immediately adjacent to each other. 5

Connected by hinges 13 to the ends of the inner end rails 11, are the upper ends of inclined legs 14 and the lower portions of each pair of legs are connected by crossed braces 15.

The upper portions of the two legs on each side of the table are connected by folding braces 16, the inner ends of which are pivotally connected 15 to each other and one brace of each pair is extended a short distance beyond the pivot point and provided with an outward projecting lip 17 that overlies the opposite brace when the braces are in open position, thereby firmly holding said 20 braces in horizontal alignment with the legs open.

Secured to the underside of the frames 10, adjacent to their outer ends, are brackets 18, to which are pivotally connected the upper ends of braces 19 and the lower end portions of these braces are curved slightly and said curved ends are pivotally connected to the parallel legs of an inverted U-shaped brace 20. 25

The lower ends of the legs of each brace are 30 pivotally connected to the table legs 14.

When the table is open, the folding braces 19 and 20 provide firm and substantial supports between the lower portions of the legs 14 and the outer ends of frames 10. 35

Mounted for transverse sliding movement upon each frame 10, is a rectangular panel 21, each panel being slightly larger than the underlying frame and the inner ends of these panels abut each other on a line between the inner end 40 rails 11.

Secured to the underside of each panel 21, is a pair of transversely disposed runners 22 of inverted U-shape in cross section and each runner overlies a transversely disposed rail 23, the 45 ends of which are secured to the inner faces of the side rails of the frames 10.

Mounted in each rail 23 are two or more anti-friction members 24, either rollers or ball bearings and which provide rolling supports for the 50 runners 22 during their movement transversely of the frames.

The rails on one side of each frame 10 are provided with openings 25, to permit the runners 22 to move when the table top sections 21 are 55

moved laterally on the frames to increase the size of the table top.

Secured to the sides of each runner 22 at the end opposite from the end that is positioned adjacent to the opening 25, through which the runner operates, is a U-shaped strap 26 that passes beneath the corresponding rail 23 and which strap at all times maintains the corresponding sliding table top section 21 in proper position 10 upon the corresponding frame 10.

Connected by hinges 27 to one of the side edges of each panel or table top section 21, is a table top section 28 that is identical in size with its companion panel 21, and under normal conditions or when the table top is folded into its smallest compass, the sections or panels 28 overlie the sections or panels 21, as illustrated in Figs. 2 and 6.

The hinges 27, that connect the panels 21 and 28 are located on the opposite side of the table from the side rails of frames 10 that are provided with the openings 25 for the accommodation of the runners 22.

For the support of various articles used during the serving of meals I have provided an auxiliary frame that is removably positioned on the central portion of the table top when the same is open and this frame comprises two pairs of legs 29, the upper ends of the members of each pair 30 being connected by a hinge 30 so that said legs may be folded toward and away from each other and the lower end of one leg of each pair carries a spring clip 31 that is adapted to engage over the edge of the table top section or panel on which 35 the auxiliary frame rests.

Connecting the legs on one side of the auxiliary frame with the legs on the other side, are rails 32 and connected by hinges 33 to the rails that connect one pair of the legs, are panels 34 that 40 provide convenient support for various small dishes and articles used by persons seated around the table.

Secured to the underside of each panel 34, adjacent to its free end, is a pair of transversely disposed cleats 35, which when the frame is properly set up for use, engage on opposite sides of the rails 32 opposite the rails to which the panels are hinged (see Figs. 4 and 5).

The various parts of the table when open for 50 use, occupy the positions as illustrated in Fig. 1 with the folded braces 16 maintaining the legs firmly in open position with braces 19 and 20 providing firm and substantial supports between the legs and the ends of the frames 10.

When it is desired to use the table top in its 55 smallest compass, the panels 28 are folded over onto the top of panels 21, as illustrated in Figs. 2 and 6 and with the panels 21 positioned above and wholly covering the frames 10.

When it is desired to increase or double the size 60 of the table top, the panels 21 carrying the panels 28, are moved transversely upon the frames 10, during which movement the runners 22 ride upon the anti-friction members 24 and said runners 65 pass through the openings 25 in the rails on one side of the table.

Thus, the edges of panels 21 that are hinged to panels 28, are brought into position on a medial line lengthwise of the frames 10 and when so 70 positioned the upper panels 28 are engaged and swung upwardly and over so as to occupy the same horizontal plane with the panels 21, with the result that the area or size of the table top is doubled.

Dotted lines in Fig. 6 show the positions of the

panels 21 and 28 and the runners 22 when the table top is open to its greatest compass.

To collapse the table or to fold it into relatively small compass for storage or transportation, panels 21 are moved into position directly 5 above the frames 10 with the panels 28 folded onto said panels 21 and after the pivoted ends of the braces 16 are swung upward and the pivoted ends of the braces 19 and 20 are swung inward, the frames 10 may be swung downward 10 against the legs 14 and said legs then folded into positions immediately adjacent to each other so that the entire structure is compactly folded 15 so as to occupy comparatively little space while not in use.

Thus it will be seen that I have provided a folding table that is relatively simple in construction, inexpensive of manufacture and very effective in performing the functions for which it is intended.

Although I have shown my invention embodied in a folding table, the construction involving the mounting of a panel for transverse sliding movement on a frame may be advantageously employed 25 in structures other than folding tables, for instance, in beds, davenports, couches and the like.

It will be understood that minor changes in the size, form and construction of the various parts of my improved folding table may be made 30 and substituted for those herein shown and described without departing from the spirit of my invention, the scope of which is set forth in the appended claims.

I claim as my invention:

1. In a folding table, a pair of frames hinged 35 to each other at their inner ends, a table top section mounted for transverse sliding movement upon each frame and a table top section hinged to one edge of each first mentioned table top section.

2. In a folding table, a pair of frames hinged 40 to each other at their inner ends, folding legs for supporting said frames, a table top section mounted for transverse sliding movement on each frame and a table top section hinged to one side 45 of each first mentioned table top section.

3. In a folding table, a pair of frames hinged to each other at their inner ends, a table top section positioned on top of each frame, transversely disposed sliding connections between each 50 table top section and the underlying frame, a table top section hinged to one edge of each first mentioned table top section and folding legs hinged to the inner ends of said frames.

4. In a folding table, a pair of frames hinged 55 to each other at their inner ends, a table top section positioned on top of each frame, transversely disposed sliding connections between each table top section and the underlying frame, a table top section hinged to one edge of each first mentioned table top section, folding legs hinged to the inner ends of said frames, folding braces between said legs and folding braces between said legs and frames.

5. In a folding table, a supporting structure 65 comprising a pair of frames arranged end to end, hinges connecting the inner ends of said frames, a pair of table top sections arranged for transverse sliding movement on said hinged frames and a table top section hinged to one of the side 70 edges of each first mentioned table top section.

6. In a folding table, a pair of frames hinged 75 to each other at their inner ends, rails transversely arranged in each frame, runners mounted for sliding movement on said rails, table top

sections secured to said runners and arranged above said frames and a table top section hinged to one edge of each first mentioned table top section.

- 5 7. In a folding table, a pair of frames hinged to each other at their inner ends, rails transversely arranged in each frame, runners mounted for sliding movement on said rails, table top sections secured to said runners and arranged above said frames, a table top section hinged to one edge of each first mentioned table top section, folding legs hinged to the inner ends of said frames for supporting the same, folding braces connecting the upper portions of the members of each pair of legs at the sides of the table, 10
- 10 above said frames, a table top section hinged to one edge of each first mentioned table top section, folding legs hinged to the inner ends of said frames for supporting the same, folding braces hinged to the lower portions of said legs and folding braces hinged at their upper ends to the outer ends of said frames and at their lower ends to the upper ends of the folding braces that are hinged to the lower portions of said legs. 15
- 15 8. In a folding table, a pair of frames hinged

to each other at their inner ends, rails transversely arranged in each frame, runners mounted for sliding movement on said rails, table top sections secured to said runners and arranged above said frames, a table top section hinged to one edge of each first mentioned table top section, folding legs hinged to the inner ends of said frames for supporting the same, folding braces connecting the upper portions of the members of each pair of legs at the sides of the table, 10

cross braces secured to the lower portions of said legs, folding braces secured to the lower portions of the legs and folding braces hinged at their upper ends to the outer ends of said frames and at their lower ends to the upper portions of the folding braces that are hinged to the lower portions of said legs. 15
